UNITED STATES PATENT OFFICE

WILLIAM H. BRETT, OF SHAKER HEIGHTS, OHIO, ASSIGNOR TO THE ENAMEL PRODUCTS COMPANY, OF CLEVELAND, OHIO, A CORPORATION OF OHIO

METAL SIGN

Application filed April 27, 1931. Serial No. 533,203.

The present invention relating as nominally indicated to metal signs, has more particular reference to a novel type of construction for securing metallic sign boards and 5 analogous articles to complementary supporting elements such as walls, posts, etc.

Heretofore it has been customary when securing metallic signs and panels to a supporting wall, to simply insert fastening 10 means such as screws, bolts, or clamps, through appropriate holes drilled through the exposed surface of the sign. The obvious result of such a construction is that in the first place protrusion of the fastening means 15 from the face of the display or panel surface becomes unsightly and, secondly, there are the disadvantages incident to the additional drilling of holes, installation of clamps, etc. It is the general object and nature of the 20 present invention to overcome such disadvantages found to exist in the prior art, and to provide a unique and convenient form of construction for such metal sign boards. It is a further object to provide a simple form of 25 securing means which is adapted to engage with an inwardly inclined flange upon the back of the sign so that the display surface shall remain unobstructed, resulting in an unusually neat and attractive appearance. To 30 the accomplishment of the foregoing and related ends, said invention, then, consists of the means hereinafter fully described and more particularly pointed out in the claims.

The annexed drawings and the following 35 description set forth in detail certain mechanism embodying the invention, such disclosed means constituting, however, but one of various mechanical forms in which the principle of the invention may be used.

40 In said annexed drawings:

Fig. 1 is an elevational front view of one form of construction embodying the principle of my invention; Fig. 2 is an elevational rear view of Fig. 1; Fig. 3 is a sectional view taken upon the line 3-3 of Fig. 1; Fig. 4 is a perspective view of the marginal securing clamp employed in the sign board construction illustrated in Figs. 1 to 3 inclusive; Fig. 5 is a section taken upon the line 5-5 of Fig. 50 2; Fig. 6 is a front elevational view partly

in section illustrative of alternative forms of marginal securing clamps; Figs. 7 and 8 are fragmentary sections taken substantially upon the lines 7-7, and 8-8, respectively of Fig. 6.

55

Directing attention more particularly to Figs. 1 to 5 inclusive, there is provided the flat display surface 1 bordered around its perimeter by the slightly raised portion 2. Such a raised border portion 2 serves to impart the properties of additional rigidity and strength to the display panel 1. The margins 3 are bent into a plane normal to that of the display surface 1. Flanges 4 are in turn bent upon the margins 3. In order to 60 secure the display panel to a suitable post 5 having an uppermost flattened portion 6, there are provided the metallic securing clamps 7. The securing clamps 7 have the 65 diagonally transversely bent portions 8 which are adapted to bear against the back surface of the sign panel 1. The lateral edge 10 of the securing clamp 7 in turn engages the interior side of the marginal flange 4. Appropriate fastening means such as bolts or rivets 70 9 may then be employed to secure the clamp 7 in position upon the flattened portion 6 of the supporting post 5. In order to facilitate 75 the rapid erection of the above described type of sign, there may be provided upon the lowermost portion of the post 5, the spindle 11 and spiral ground bit 12.

80

When it is desirous to secure the metallic sign board to a flat wall surface, I provide the alternative forms of securing clamps illustrated in Figs. 6 to 8 inclusive. One form of clamp consists of the flat body portion 16 having the reversely bent clip 17 which is adapted to engage with the marginal flange 4. Suitable fasteners 18 such as wood screws, bolts or nails, may be used to attach the clamps 16 to the supporting wall.

85

When an exceptionally neat appearing installation is desired, there is provided the type of clip illustrated in the lower right hand fragment of Fig. 6 and in the sectional Fig. 8. Such form of securing clamps consists of the flat body portion 19 having the slightly raised marginal portions 20 which are adapted to engage with and secure the marginal flanges 370

4 of the metallic sign 1. The fastening means 18 are inserted through the body portion 19 and are positioned interiorly of the outside edges of the sign.

5 It will thus be seen that the latter form of construction provides securing clamps which do not mar, injure or scratch the display surface of the sign; and which are adapted to rigidly secure the sign against horizontal or 10 vertical movement.

10 Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

20 1. A metal sign comprising in combination, an outer display wall, margins on said wall, flanges on said margins parallel to said wall, and securing clamps between said flanges and said wall, there being bent portions on said 25 clamps extending in a plane normal to the plane of said wall, said bent portions having a width substantially equal to that of said margins.

30 2. A metal sign comprising in combination, an outer display wall, margins on said wall, flanges on said margins parallel to said wall, and securing clamps between said flanges and said wall, there being bent portions on said 35 clamps extending in a plane normal to the plane of said wall, said bent portions having a width substantially equal to that of said margins and being angularly inclined with respect to said margins.

3. A metal sign comprising in combination, 40 an outer display wall, inwardly turned margins thereon, flanges on said margins parallel to said wall, and means for securing said sign to a supporting element comprising a plurality of clamps having flat portions and 45 bent portions, said flat portions engaging said flanges and said supporting element and said bent portions extending from said flat portions to said wall.

4. A metal sign comprising in combination, 50 an outer display wall, inwardly turned margins thereon, flanges on said margins parallel to said wall, and means for securing said sign to a supporting element comprising a plurality of clamps having flat portions and bent 55 portions, said flat portions engaging said flanges and said supporting element and said bent portions extending from said flat portions to said wall, said bent portions having a width slightly less than that of said margins.

60 Signed by me this 24th day of April, 1931.
WILLIAM H. BRETT.
